UNITED STATES PATENT OFFICE.

EMERSON G. REED, OF WILKINSBURG, PENNSYLVANIA, ASSIGNOR TO WESTINGHOUSE ELECTRIC AND MANUFACTURING COMPANY, A CORPORATION OF PENNSYLVANIA.

TRANSFORMER.

1,227,314.

Specification of Letters Patent. Patented May 22, 1917.

Application filed November 5, 1913. Serial No. 799,274.

To all whom it may concern:

Be it known that I, EMERSON G. REED, a citizen of the United States, and a resident of Wilkinsburg, in the county of Allegheny and State of Pennsylvania, have invented a new and useful Improvement in Transformers, of which the following is a specification.

My invention relates to stationary inductive apparatus, and it has for its object to 10 provide an improved transformer structure which will insure adequate cooling for the transformer coils, and, at the same time, will require a minimum amount of active material.

15 Heretofore, in transformers of the so-called cruciform or distributed shell type, it was usual to space the several coils comprising the winding from each other in such a way as to provide an oil or ventilating duct or ducts which extended through the body of the winding and surrounded the periphery of the inner coils. By this form of construction, ventilating means was provided which was effective in maintaining 25 the temperature of the several parts of the winding at a safe value. The core structure comprised a plurality of magnetizable circuits preferably made of laminated iron, each of which embraced the oil duct or ducts surrounding the inner coils. As a 30 result, a large quantity of active material was employed in the core structure which was not essential for either magnetic or electrical reasons and which added materially to the weight and the cost of the 35 transformer.

In my transformer, I propose to provide oil ducts between the several coils which will be so positioned that the magnetic circuits employing the greater quantity of 40 active material, such as iron, will not embrace the aforementioned ducts. With my type of construction, adequate cooling of the transformer coils is assured, while a material saving in the amount of laminated 45 iron is effected.

In order to disclose my invention more fully, reference may be had to the following description and the accompanying drawing 50 in which Figure 1 is a sectional plan view, and Fig. 2 is a view, in elevation, of an assembled transformer core and winding which embodies a form of my invention.

Referring to the drawings, the structure 55 illustrated comprises a plurality of core

members 1, 2, 3 and 4 which embrace coils 5 and 6. The core members 1 and 3 are alike as are also the core members 2 and 4. Each of the members 1 and 3 is provided with an inside portion 7 the cross sectional area of which is materially less than those of the outer side and ends. Side portions 8 are expanded by means of interleaved laminations in order to increase the cross sectional areas of the magnetic circuits exteriorly of the coils 5 and 6. The two inner side portions 7 of the core members 1 and 3 abut against each other, and two corresponding side portions 9 of the core members 2 and 4 abut against the sides of the 60 first mentioned portions, substantially as shown in Fig. 1. By thus grouping the core portions 7 and 9, a maximum amount of iron may be embraced by a minimum mean length of turn in the coils 5 and 6, thereby reducing the cost of the transformer. 75

The coil 6 is surrounded by the coil 5 which fits closely thereto along the sides embraced by the core members 1 and 3. Interposed between the adjacent surfaces of the sides of the coils embraced by the core members 4 and 2, are oil ducts 10. Inasmuch as the core members 1 and 3 which contain the greater portion of the active magnetizable material, preferably 80 laminated iron, do not embrace any air ducts, a material saving in the total amount of iron is effected. At the same time, adequate cooling facilities for the coils 5 and 6 are provided by the air ducts 10 which 85 are embraced by the core members 2 and 4. 90

The quantity of active material comprised in the core members 2 and 4 is much smaller than that comprised in the core members 1 and 3, and, therefore, the material wasted by providing the ducts 10 is negligible, as 95 compared with the old form of construction, as previously explained, although the width of the said ducts may be substantially increased. I have found that very satisfactory operating results may be obtained by making the core members 2 and 4 of such dimensions as to include about 25 per cent. of the total iron in the core 100 structure.

I claim as my invention:

1. In a shell-type transformer, the combination with nested coils provided with spaced ventilating ducts, of a core comprising relatively narrow and relatively wide 110

- members, the relatively narrow members embracing the said coils and ducts, and the relatively wide members embracing the coils only.
5. 2. In a shell-type transformer, the combination with a nest of substantially rectangular coils provided with ventilating ducts extending along the shorter sides only thereof, of a core comprising relatively narrow and relatively wide members, the relatively narrow members embracing the said ducts and the shorter sides of the coils, and the relatively wide members embracing the longer sides only of the coils.
- 10 15. 3. In a shell-type transformer, the combination with a plurality of nested coils having spaced ventilating ducts positioned intermediate thereof, of a core comprising a plurality of unlike members, the larger ones of which embrace unspaced portions only of the said coils.
- 20 25. 4. In a shell-type transformer, the combination with a plurality of substantially rectangular coils which are nested and provided with spaced ventilating ducts intermediate two opposite sides thereof, of a core comprising a plurality of relatively narrow and relatively wide members, the relatively narrow members embracing the coils and ventilating ducts, and the relatively wide members embracing only the coils.
- 30 5. In a shell-type transformer, the combination with a nest of substantially rectangular coils provided with ventilating ducts extending along the shorter sides only thereof, of a core comprising unlike members some of which embrace the shorter sides of said coils and ducts, and others of which embrace the longer sides of said coils only.
6. In a cruciform-type transformer, the combination with a nest of coils which are in intimate contact with one another on some of their sides and are spaced apart from one another on other sides to provide ventilating ducts, of a core comprising a plurality of members, some of which embrace those portions only of said coils which are spaced from one another and some of which embrace those portions only which are in intimate contact with one another.
- In testimony whereof, I have hereunto subscribed my name this 31st day of Oct. 1913.

EMERSON G. REED.
